FEED-OUT MECHANISM

Berthel F. Madsen, Arlington Heights, and John E. Randolph, Chicago, Ill., assignors to Teletype Corporation, Chicago, Ill., a corporation of Delaware

Application January 27, 1956, Serial No. 561,724

6 Claims. (Cl. 197—133)

The present invention pertains to an improvement in a telegraph page printer and more particularly to a form feed-out mechanism for a page printer of the type described in the United States Patent No. 2,505,729 issued to Mr. W. J. Zenner on April 25, 1950.

One object of the present invention is to provide a telegraph printer with a form feed-out device which operates independently of the line feed mechanism of the printer.

Another object of the present invention is to provide a telegraph printer with an auxiliary motor for advancing a platen through a predetermined amount of advance.

These and other objects will be apparent from the following description when it is considered in conjunction with the drawings wherein:

Fig. 1 is an end view of a printer embodying the present invention with the electromagnet removed; and

Fig. 2 is an enlarged perspective showing the switch actuating and line feed disconnecting device in detail with the electromagnet in place.

The present invention accomplishes the rapid, uninterrupted feed-out of the record by employing a small, high speed, low inertia motor to drive the platen through a toothed belt drive. The signal controlled mechanism for disengaging the normal line feed and energizing the form feed-out motor is activated by an electromagnet.

Referring now to Fig. 1, a platen 11 has a line feed gear 12 keyed to its shaft so as to be rotatable by the line feed pawls 13 in a manner to be described. A second gear 14 is similarly keyed to the platen shaft and is adapted to drive or be driven by a belt 16 which connects the gear 14 with an idler gear 17. Keyed to the same shaft as the gear 17 is a second idler gear 18 which is engaged to be driven by the output gear 19 on an electric motor 21. The idler gear 18 is engaged with a program wheel 22 so that the program wheel 22 is advanced proportionately to the advance of idler gear 18 and hence proportionately to the advance of the platen.

The motor 21 is electrically connected to a microswitch 23, which is in turn controlled by the feedout assembly 24.

The line feed pawls 13 are mounted on eccentrics 26 so as to be alternately moved into engagement with the gear 12 and downward to impart rotation to the platen 11. The eccentrics 26 are driven through a line feed clutch (not shown) which is tripped by the line feed signal to advance the platen one line.

A lever 27 is pivotally attached to the frame at a point 28 and is adapted to be constantly oscillated by any convenient means such as the type box clutch (not shown). An interponent 29, pivotally fastened on the lever 27, connects the lever 27 with a slide bar operating blade 31 which is constantly oscillated about its pivot point 32.

The feed-out assembly 24 which is most clearly illustrated in Fig. 2 is comprised of an operating bar, or

2

slide bar 33 slidably mounted on the frame, a pawl 34 mounted on the frame at 30 and articulated to a pin 36 which is mounted in a pair of elongated holes in the line feed pawls 13, a program pawl 37 pivotally mounted on the frame at pin 48, which pin also has the bifurcated portion 38 of the operating bar 33 slidably mounted thereon, a hinged blocking member 39 secured to the bar 33 so as to be cooperable with the bar operating blade 31, an electromagnet 41, an armature 42 associated with the magnet 41 and articulated to the hinged member 39, and the microswitch 23 so positioned as to be operable by the leftward movement of the operating bar 33.

In operation, the lever 27 is constantly oscillated by an eccentric cam on the type box clutch which is not shown but is described in the aforementioned Zenner patent, said patent being a part hereof by reference. Oscillation of the lever 27 imparts an oscillatory movement to the operating blade 31 through the interponent 29. When the electromagnet 41 is not energized, its armature 42 is moved toward the operating bar 33 by the spring 43 to thereby pivot the hinged member 39 clockwise out of the path of the operating blade 31. When the feed-out signal is received, the magnet 41 is energized in the well known manner to draw up the armature 42 and thereby rotate the hinged member 39 into the path of the operating blade 31. As the blade 31 is oscillated counterclockwise, it strikes the hinged member 39 and carries it to the left thereby moving the operating bar 33 to the left against the urging of its spring 46. At the end of the counterclockwise oscillation of the blade 31, the shoulder 44 of the bar 33 cooperates with the latch plate 35 to hold the operating bar 33 in its leftward position. The leftward movement of the bar 33 moves the lower extension of its bifurcated portion 38 against the switch 23 to energize the motor 21 and simultaneously moves the line feed pawls 13 out of engagement with the platen gear 12 by moving the pawl 34 to the left against the urging of the spring 47. The pawl 34 is pivotally attached at 30 and the pin 36 so that the spacing pawls 13 are rotated counterclockwise out of engagement with the gear 12. The motor 21 operates to drive the gears 17 and 18 which in turn drive the platen 11 and the program wheel 22. After the platen 11 has been rotated a predetermined amount, the program wheel will have been rotated until a selectively attached cam blade 25 contacts the tripping pawl 37 and rotates it counterclockwise about the pin 48 to move the tripping pawl extension 49 against the bar 33 to disengage the shoulder 44 from the latching plate 35 so as to allow the bar 33 to be returned to its unoperated position by its spring 46. Returning of the bar 33, of course, reverses the operating procedure so that the switch 23 de-energizes the motor 21 and the pawls 13 are once more engaged with the platen gear 12. While only one cam blade 25 is shown on the program wheel 22, it should be understood that as many cam blades as are convenient may be employed with the present invention.

While the present invention has been illustrated in a specific embodiment, it is of course understood that the invention may be used in other embodiments without departing from the spirit and scope thereof.

What is claimed is:

1. In a telegraph printer, a platen, an eccentrically mounted feed pawl means normally engaged for selectively advancing said platen, a power means independent of the printer operable to rotate said platen, a switch for actuating said power means, a slide bar articulated to said feed pawl means, said bar being operable to simultaneously disengage said feed pawl means and ac-

tuate said switch; a constantly oscillating lever driven by the printer; an electromagnet, an armature means controlled by said magnet for conditioning said slide bar for operation by said oscillating lever, means for selectively energizing said magnet, latching means for holding said slide bar operated and means actuated by the advance of said platen to a predetermined point for rendering said latching means ineffective.

2. In a telegraph printer, a platen, a gear operable to rotate said platen, a pair of eccentrically mounted pawls normally engaged with said gear, a first power means for selectively operating said gear through said pawls, a second power means for rotating said platen, means articulated to said pawls for disengaging said pawls from said gear, means controlled by the operation of said disengaging means for actuating said second power means, means for operating said disengaging means operated, a program wheel adapted to be rotated in proportion to the rotation of said platen, and means controlled by a predetermined amount of program wheel rotation for rendering said latching means ineffective.

3. In combination in a motor powered recorder, a rotatable platen, a first gear keyed to said platen, a second gear keyed to said platen, a pair of line feed pawls engaged with said first gear, means for selectively operating said pawls by the recorder motor, power means engaged with said second gear for advancing said platen, said power means being independent of the recorder motor, a switch adapted to operate said power means, an operating bar adapted to actuate said switch articulated to said line feed pawls, a constantly oscillating lever adaptable to move said operating bar into contact with said switch, and a means for engaging said lever with said operating bar, whereby said pawls are disengaged from said first gear simultaneously with the actuation of said power means.

4. In a telegraph recorder which includes a platen, a gear keyed to the platen, line feed means normally engaged with said gear, and a program wheel adapted to be rotated by said platen, an auxiliary feed-out mechanism comprising, an electric motor means operable to rotate said platen, a power source including a switch for actuating said motor, a slide bar operable to actuate said switch, resilient means for holding said slide bar unoperated, means controlled by the operation of said

slide bar for disengaging said line feed means, a pawl pivotally mounted on said slide bar, a constantly moving operating means, an electromagnet, an armature means operable by said magnet to pivot said pawl into the path of said operating means, whereby said slide bar is moved to its operated position, means for selectively energizing said magnet, means for latching said slide bar in its operated position, and unlatching means controlled by said program wheel.

5. In a telegraph printer, a platen, a first means controlled by the printer and normally engaged to rotate said platen, a second means independent of said printer and operable to rotate said platen, a power source, a switch for connecting said second means to said power source to actuate said second means, a slide bar articulated to said first means and operable to simultaneously disengage said first means and actuate said switch, a constantly oscillating lever driven by said printer, an electromagnet, an armature controlled by said magnet for conditioning said slide bar for operation by said oscillating lever, means for selectively energizing said magnet, latching means for holding said slide bar operated, and means actuated by the rotation of said platen to a predetermined point for rendering said latching means ineffective.

6. In a telegraph printer, a platen, a first means controlled by the printer and normally engaged to rotate said platen, a second means independent of said printer and operable to rotate said platen, a power source, a switch for connecting said second means to said power source to actuate said second means, a slide bar articulated to said first means and operable to simultaneously disengage said first means and actuate said switch, a constantly oscillating lever driven by said printer, means for causing operation of said slide bar by said oscillating lever, latching means for holding said slide bar operated, and means actuated by the rotation of said platen to a predetermined point for rendering said latching means ineffective.

UNITED STATES PATENT OFFICE
CERTIFICATE OF CORRECTION

Patent No. 2,851,142

September 9, 1958

Berthel F. Madsen, et al.

It is hereby certified that error appears in the printed specification of the above numbered patent requiring correction and that the said Letters Patent should read as corrected below.

Column 3, line 18, after "means" insert --, latching means for holding said disengaging means --.

Signed and sealed this 12th day of May 1959.
